UNITED STATES PATENT OFFICE

STUART JOHNSON, OF CONGLETON, ENGLAND, ASSIGNOR TO HUGH C. EDMISTON, OF NEW YORK, N. Y.

DESIGN FOR A PLATE OR SIMILAR ARTICLE

Application filed November 7, 1931. Serial No. 41,648. Term of patent 7 years.

To all whom it may concern:

Be it known that I, STUART JOHNSON, a subject of the King of Great Britain, residing at Congleton, county of Cheshire, England, have invented a new, original, and ornamental Design for a Plate or Similar Article, of which the following is a specification, reference being had to the accompanying drawings, forming part thereof.

Figure 1 is a plan view of a plate showing my new design in a sufficient portion to show

the complete design and the balance of the design being merely a repetition of the ornamentation shown and running around the entire plate.

Figure 2 is a cross-sectional view of the same.

I claim:

The ornamental design for a plate or similar article as shown and described.

STUART JOHNSON.
